UNITED STATES PATENT OFFICE.

EDWARD M. HEYLMAN, OF SOUTH BEND, INDIANA, ASSIGNOR TO OLIVER CHILLED PLOW WORKS, OF SOUTH BEND, INDIANA.

FOLLOWER-WHEEL CONSTRUCTION FOR PLOWS.

1,234,762.

Specification of Letters Patent. Patented July 31, 1917.

Application filed October 21, 1915. Serial No. 57,116.

To all whom it may concern:

Be it known that I, EDWARD M. HEYLMAN, a citizen of the United States, and a resident of South Bend, in the county of Saint 5 Joseph and State of Indiana, have invented certain new and useful Improvements in Follower-Wheel Construction for Plows; and I do hereby declare the following to be a full, clear, and exact description of the 10 invention, such as will enable others skilled in the art to which it appertains to make and use the same.

This invention relates to improvements in plows and more particularly to means for 15 operating a rear supporting wheel for engine gang plows such as disclosed in my copending application filed even date here-with.

One object of my present invention is to 20 provide simple and efficient means for supporting the rear end of the plow through the medium of a follower wheel, and for operating said wheel in a manner to effect the raising and lowering of the rear end of 25 the plow.

A further object is to provide means to normally hold the follower wheel axle in 30 position and cause said wheel to properly trail in the furrow by the plow base, and at the same time permit said wheel to caster when the plow is turned.

A further object is to provide simple 35 means for adjusting the mounting of the follower wheel as to regulate the depth which the rear end of the plow base may enter the ground.

A further object is to provide simple and 40 efficient stop devices to limit the movements of the follower wheel mounting.

With these and other objects in view, the 45 invention consists in certain novel features of construction and combinations of parts as hereinafter set forth and pointed out in the claims.

In the accompanying drawings; Figure 1 is a side elevation of a plow showing the 50 application of my improvements and the positions assumed by the parts when the plow base is in working position; Fig. 2 is a similar view, partly in section, showing the positions of the parts when the plow is raised; Fig. 3 is a plan view, and Figs. 4, 5 and 6 are views of certain details.

1 represents a plow beam bent downwardly

at its rear end to form a standard 2, the 55 latter carrying a plow base 3.

Plate brackets 4, 4, are secured to respective sides of the standard portion of the beam and project rearwardly therefrom. A bearing sleeve 5 is pivotally supported at 6 60 between the rearwardly projecting lower portions of the plate brackets 4 and receives the upright portion of the axle 7, the lower end of which is mounted in the hub of a follower wheel 8 which serves to support the 65 rear end of the plow.

The axle 7 projects above the upper end of the bearing sleeve and has a head 9 secured thereto, said head being made with radial projections 10 for a purpose presently 70 explained. A bracket arm 5^a projects rearwardly from the upper end of the bearing sleeve and affords a mounting for a plunger 11 having radial projections 12 at its forward end bearing against the radial projections 10 at the upper end of the axle 7,— rearward movement of said plunger being resisted by a spring 13. This construction provides a yielding holding or locking means for the caster or follower wheel axle 80 and serves to insure the retention of said wheel in proper alignment with the plow during the operation of the same, but at the same time permitting the wheel to caster when the plow is turned when subjected to 85 abnormal lateral resistance.

Turning movement of the follower wheel axle is limited by the engagement of a stop 14 with shoulders, such as shown at 15, at the upper end of bearing sleeve 5. 90

A lever 16 is pivoted intermediate of its ends between the upper ends of the plate brackets 4 and the lower end of this lever is disposed between the standard portion of the beam 1 and an arm 17 projecting forwardly from the upper portion of the bearing sleeve 5 so as to be in position to engage said arm. 95

When the plow is in working position, as shown in Fig. 1, the bearing sleeve 5 will 100 incline forwardly, with the arm 17 bearing against the lower arm of the lever 16. A set screw 18 passes through the lower arm of the lever 16 and engages the standard portion of the plow beam. By means of this 105 screw, the inclination of the bearing sleeve and axle may be changed so as to depress or raise the follower wheel and thus adjust

the depth of plowing of the rear end of the plow base.

A balance spring 19 is connected at one end with the upper arm of the lever 16 and 5 at the other end to the plow beam for assisting in the raising of the plow when said lever is operated. For operating said lever, a rod 20 is attached thereto, the other end of said rod being connected with suitable 10 operating means (not shown) at the forward portion of the plow structure,—the mechanism, for instance, shown in my application for patent filed concurrently herewith.

15 It will be readily understood that when the lever 16 is operated to move its upper arm forwardly, its lower arm will move rearwardly and force the bearing sleeve rearwardly on its pivotal support, thus 20 causing the wheel to tend to move in the arc of a circle, but as this wheel is bearing upon the ground, the rear end of the plow will be raised. The extent of movement of the lever 16 is sufficient to move the bearing sleeve from the inclined position shown in 25 Fig. 1 to the vertical position shown in Fig. 2, and to limit the movement of the bearing sleeve so that it may not be rearwardly moved beyond a vertical position, 30 said bearing sleeve is provided at its lower end with an arm 21 which projects forwardly between the bracket plates 4 and engages a stop 22 on one of said plates, as shown in Fig. 2.

35 When the bearing sleeve shall have been moved to the position shown in Fig. 2, the upper portion of the axle will be disposed vertically, which is the best position which it may assume when the plow structure is to 40 be transported over the ground and when a corner is to be turned.

Various slight changes might be made in the details of construction of my invention without departing from the spirit thereof or limiting its scope and hence I do not wish 45 to restrict myself to the precise details herein set forth.

Having fully described my invention what I claim as new and desire to secure by Letters-Patent, is:—

1. The combination with a plow and a bracket at the rear end thereof, of a bearing sleeve pivoted near its lower end to said bracket, a follower wheel, an axle for said follower wheel mounted in said bearing 55 sleeve, a lever pivoted to said bracket projecting between the plow and bearing sleeve and engaging a part on said sleeve when the latter is in a normal inclined working position, and a set screw passing through said lever and engaging the plow for regulating the depth of plowing.

2. The combination with a plow and a bracket secured to the rear end thereof, of a bearing sleeve pivoted near its lower end 65 to said bracket, a follower wheel, an axle for said wheel mounted in said bearing sleeve, means for moving said bearing sleeve on its pivotal support from an inclined to a vertical position, an arm projecting forwardly from the lower portion of said sleeve, and a stop to be engaged by said arm 70 to limit the rearward pivotal movement of said sleeve.

In testimony whereof, I have signed this 75 specification in the presence of two subscribing witnesses.

EDWARD M. HEYLMAN.
